UNITED STATES PATENT OFFICE.

WILLIAM C. MEYER, OF BOSTON, MASSACHUSETTS, ASSIGNOR TO UNITED SHOE MACHINERY COMPANY, OF PATERSON, NEW JERSEY, A CORPORATION OF NEW JERSEY.

TENSION MECHANISM FOR SEWING-MACHINES.

1,030,742.

Specification of Letters Patent. Patented June 25, 1912.

Application filed June 16, 1902, Serial No. 111,806. Renewed December 9, 1904. Serial No. 236,240.

To all whom it may concern:

Be it known that I, WILLIAM C. MEYER, of Boston, county of Suffolk, State of Massachusetts, have invented an Improvement in

6 Tension Mechanism for Sewing-Machines, of which the following description, in connection with the accompanying drawings, is a specification, like characters on the drawings representing like parts.

10 This invention relates to sewing machines and has for its object to improve and simplify the construction of means for operating the tension-device for the needle-thread whereby a very hard tension may be applied 15 to the needle-thread when the stitch is being set, which is of such a degree as to practically constitute a yielding locking-device for the needle-thread, and whereby said tension will be partially relieved when the needle-thread 20 is being drawn from its supply, as for instance when the pull-off is operating to pull off a measured length of thread from the supply, and furthermore whereby said tension will be wholly relieved whenever desired, as for instance when the work is being drawn from the machine.

The invention herein shown is intended as an improvement upon the sewing machine shown in U. S. patent to French and Meyer 25 #790,790, dated May 23, 1905, and is herein illustrated as applied to the sewing machine shown in said patent, yet the novel features thereof may be applied to other sewing machines and advantageously used.

30 Figure 1 shows in front elevation a sewing machine embodying this invention. Fig. 2, is a left hand side elevation of the sewing machine shown in Fig. 1. Fig. 3, is a longitudinal vertical section of the tension-device, its operating lever being broken off and represented in its several different positions. Fig. 4, is a detail of the means provided for operating the tension-device to wholly relieve the tension. Fig. 5, is a detail of the 35 arm n^6 shown in Fig. 4. Fig. 6, is a detail showing in front elevation the means for wholly relieving the tension. Figs. 7 and 8 are details of the actuating-device for the means for operating the tension-device which is operated by the main shaft.

The main frame comprises essentially the upright or column A surmounted by a table A', having erected thereon several vertical uprights A² which are constructed and arranged to afford bearings for the main shaft

B which has secured to it several operating cams, and said uprights also afford bearings for the rod or bar C and for the other operating parts of the machine.

a represents the wax pot.

b represents the thread-wheel of the tension-device, it being shown as a wheel having a grooved periphery and mounted to freely revolve on the bar b' projecting horizontally from the main frame. A friction disk b², see Fig. 3, is mounted to slide along on said bar b' and to bear frictionally against one side or face of said thread-wheel to thereby apply the required tension, and said friction disk comprises a circular end portion or face and a hub 20, which latter is made long enough to give to the disk a good and sufficient bearing on the bar b'. A spiral spring b³ surrounds the bar b' which bears at one end against the hub 20 of the friction disk and at the opposite end against a small hand wheel b⁴ which is arranged on and in engagement with a threaded portion of the bar b' and by turning said hand wheel in one or the other direction the pressure exerted by said spring upon the friction disk will be varied and the tension on the thread accordingly regulated.

A ring a⁵ is mounted to slide along on the hub 20 of the friction disk and a spiral spring a⁶, made considerably larger in diameter than the spiral spring b³, is placed outside of said spiral spring b³ which bears at one end against said ring a⁵ and at the other end against a ring a⁷ which is adjustably mounted on the hub of the hand wheel b⁴. The spring a⁶, like the spring b³, exerts its pressure upon the friction disk b² and the pressure exerted by said spring a⁶ is regulated by adjustment of the ring a⁷.

The bar b' is made hollow and receives within it a rod b⁸, the inner end of which has a transverse hole through it through which is driven a pin b⁹ which is made long enough to project a short distance from the rod at each side, or in lieu of said pin the rod b⁸ may be provided with any form of laterally projecting pins or studs. Both projecting ends of said pin b⁹ pass through longitudinal slots b⁷ in the hollow bar b' and also through longitudinal slots a⁸ in the hub of the friction disk b² and enter holes in the ring a⁵. The ring a⁵ is thus rigidly connected to the pin and consequently to the rod b⁸ and by moving said rod b⁸ in the

direction of its length said ring will be moved along on the hub of the friction disk and thereby caused to engage or disengage the end portion of said friction disk according to the direction of movement of the rod b^5 .

When the rod b^5 is moved in the direction of the arrow thereon a short distance the ring a^6 will be correspondingly moved away 10 from the friction disk and the pressure of the spring a^6 removed, but at such time the pressure of the spring b^3 will be still exerted on the friction disk and as a result the tension on the thread is partially but not wholly 15 relieved, and when said rod b^5 is moved farther in the direction of the arrow, the pin b^6 will be moved along to the end of the slots in the hub of the friction disk, and will then engage said hub and move the 20 friction disk away from or out of engagement with the thread-wheel and as a result the tension on the thread is wholly relieved.

It is designed and intended that the springs b^3 and a^6 shall exert their combined 25 pressures on the friction disk so as to apply a very hard tension to the thread when the stitch is being set, and that the spring b^3 , only, shall exert its pressure on the friction disk when the needle-thread is being drawn 30 from its supply, the tension being thereby partially relieved, and that the pressure of both of said springs shall be removed and the tension wholly relieved whenever desired, as for instance when drawing the 35 work from the machine. These several results are all accomplished by moving the rod b^5 longitudinally more or less. As a means for moving said rod b^5 longitudinally a cam-lever b^8 is provided, having a bifurcated end, which straddles the projecting end of said rod b^5 , and is pivotally connected thereto, the cam portions b^{10} of said lever bearing upon a washer or plate b^9 placed on the projecting end of said rod b^5 and bearing 40 against the end of the bar b' , so that as said cam-lever b^8 is turned on its pivot in one direction the rod b^5 will be drawn from the hollow bar b' and as said cam-lever is turned back into the position represented by 45 full lines Fig. 3, said rod will be restored to its normal position.

The cam-lever b^8 will be moved more or less as required to in turn move the rod b^5 far enough to remove the ring a^6 from its 50 engagement with the friction-disk or further to also remove the friction-disk from its engagement with the thread-wheel. Thus the cam-lever is adapted to occupy three different positions, as represented by full 55 and dotted lines Fig. 3. Thus when the cam lever occupies the full line position Fig. 3, a hard tension is applied, and when it occupies the first dotted line position, next the full line position, the tension is partially relieved, and when it occupies the second dot-

ted line position the tension is wholly relieved.

The cam lever normally occupies a position in alinement with the rod b^5 as shown in full lines Fig. 3, and is held in this position by the springs acting to draw said rod b^5 inward into the hollow bar, and whenever said cam lever is moved to an abnormal position, as for instance into either of the dotted line positions shown in Fig. 3, it 75 will be automatically restored to normal position when the force employed to move it is relieved.

The cam-lever b^8 is formed with a hand-piece by which it may be operated by hand 80 at any time desired.

To operate the tension-device automatically at predetermined times, as for instance to apply a hard tension when each stitch is being set and to partially relieve the tension 85 while the needle-thread is being drawn from its supply for the next stitch, suitable means will be provided and for the purposes of illustration substantially the same means may be employed as is employed in the patent heretofore referred to for operating the tension-device to relieve the tension on the needle-thread.

An arm b^{12} projects from a hub b^{13} mounted on a bar b^{20} stationarily supported by the frame and said arm b^{12} has at its outer end an adjusting-screw or stud b^{14} properly disposed to strike the cam-lever b^8 when said arm is lifted or brought forward to thereby move said cam-lever from the full line position shown in Fig. 3, to the first dotted line position therein shown, thereby moving the ring a^6 in a direction away from the friction-disk b^2 and consequently partially relieving the tension by removing the pressure 100 of the spring a^6 . An arm or lever b^{15} see dotted lines Fig. 2 projects rearwardly from said hub b^{13} having a laterally projecting stud at its extremity, with or without a roll thereon, which enters a cam-groove, not shown, but formed in one side or face of a cam-wheel or disk D, said cam-groove being formed in the right hand side or face of said disk. As the arm b^{15} is moved by said cam-wheel or disk D the hub b^{13} will be 110 rocked and the arm b^{12} correspondingly moved to operate the cam-lever b^8 . I do not desire to limit my invention to the particular means herein shown for thus automatically operating the cam-lever b^8 at predetermined times to partially relieve the tension.

c represents a pull-off for the needle-thread which operates in conjunction with the other parts to be described to draw off 125 of the thread supply a measured quantity or length of needle-thread for the next stitch, and as herein shown said pull-off consists of a bell-crank lever pivoted at c' to the frame having a roll c^2 at the extremity of one of 130

its arms over which the thread 2 passes and having the extremity of its other arm connected by a rod or bar c^3 with a slotted arm c^4 projecting from a hub mounted on and 5 adapted to move on the bar c' . To said hub a rearwardly projecting arm c^6 is secured which has at its extremity a stud c^7 , with or without a roll thereon, which enters a cam-groove, not shown, formed in one side or 10 face of the cam-wheel or disk D which is secured to the main shaft B, said cam-groove being formed in the right hand side or face of said disk. The rod or bar c^3 is adjustably connected with the slotted arm c^4 so that the 15 pull-off c may be adjusted in such a manner that it may operate to pull off more or less needle-thread from the thread supply.

A thread-clamp is provided next the pull-off by means of which the needle-thread may 20 be held while the pull-off is operating to draw off a measured quantity or length of thread. The thread-clamp is herein shown as a grooved roll e over which the thread 2 passes, mounted on a fixed stud e' , and a 25 thread-engaging finger e^2 pivoted at e^3 having its lower end constructed and arranged to clamp the thread 2 in a groove formed in the periphery of said roll e and having its upper end connected by a rod or bar e^4 with 30 an arm e^5 projecting from the hub b^{13} which is mounted to oscillate on the bar b^{20} . The thread-engaging or locking finger e^2 is operated simultaneously with the arm b^{12} which operates the cam-lever b^8 . The 35 thread-clamp operates to clamp and hold the needle-thread while the pull-off c draws a measured length or quantity from the needle thread supply, but a pull-off and thread-clamp for the needle-thread whereby 40 a measured quantity is or may be drawn from the thread supply for the next stitch to be formed is shown in United States Patent #412,703, dated October 3d, 1889 and consequently is not broadly herein claimed, except as hereinafter stated.

Instead of operating the cam-lever b^8 by manipulating the hand piece whenever it is desired to wholly relieve the tension, as for instance when withdrawing the work from 50 the machine, I have herein provided means adapted to be operated by turning the driving-wheel or main shaft backward to accomplish this result, which means will be restored by turning said wheel or shaft in 55 the opposite direction, but such means, however, is not connected with the cam lever, hence said lever is free to be operated by the means previously described or by hand.

An arm n is loosely mounted on the stationarily supported bar b^{20} , which projects therefrom toward the cam-lever b^8 , and has at its extremity a forward extension n' which is adapted to abut against and thereby engage said cam-lever b^8 and move it 65 whenever the arm n is swung forward on the

bar b^{20} . A two-faced collar-engaging arm n^6 is loosely connected to a rearward extension n^5 on the arm n , so as to oscillate, and extends toward and is continuously held pressed into engagement with a collar n^7 , 70 which is secured to the main shaft B of the machine, thereby frictionally engaging said collar. A flat spring n^2 is attached at its upper end to a collar n^3 on the bar b^{20} , its lower end being free and bearing against a shoulder n^4 formed on the extension n^5 on the arm n , and said spring acts to move the arm n in a direction away from the cam lever and also to thrust the arm n^6 into continuous engagement with the collar n^7 . The collar n^7 80 can be turned backward by turning the driving-wheel by hand, and will be turned forward in the regular running of the machine. The collar n^7 is here shown as formed or provided with a recess n^8 , see dotted lines 85 Fig. 4. The outer end of the arm n^6 is formed or provided with two curved faces n^9 , n^{10} , either one of which is adapted to be brought into concentric relation to and in frictional engagement with the collar n^7 , and 90 with an intermediate projection or tooth n^{12} between said curved friction surfaces, and at a point by the side of said projection the end of the arm is cut away or recessed in order that said projection may protrude so as to 95 enter the recess in the collar n^7 , like unto the tooth of a gear.

As the collar n^7 is turned backward, as for instance in the direction of the arrow, Fig. 4, the recess formed therein will receive the 100 projection n^{12} , and then acting as if said projection was a tooth will move the arm n^6 downward on its pivot until said recess passes by said projection, and the curved engaging surface n^{10} is brought into concentric relation to and in frictional engagement with the collar, and thereafter further rotary movement of the collar n^7 in this direction will not act to further move said arm. When the collar n^7 is turned in the opposite direction to the arrow shown in Fig. 4, the recess n^8 will again be brought into 110 position to receive the projection n^{12} , and the arm n^6 will be moved upward on its pivot and the collar-engaging surface n^9 brought 115 into concentric relation to and in engagement with the collar and further rotary movement of the collar n^7 in this direction will not act to further move said arm.

The arm n^6 is made of such length and the 120 two curved engaging faces or friction surfaces n^9 , n^{10} so disposed that when the engaging face n^9 is in engagement with the collar n^7 said arm will occupy a position substantially radial to the axis of the collar n^7 , 125 and when said arm is moved on its pivot and the engaging face n^{10} is brought into engagement with the collar n^7 , said arm will occupy a position more nearly tangential to the collar. This result is accomplished by 130

- locating the two frictional surfaces n^9 , n^{10} , at different distances from the pivot of the arm. As the arm is moved on its pivot from one position to the other it will be moved longitudinally, and thereby operate to move the arm n on its pivot b^{20} , it being understood that the spring n^2 acts to always keep the arm n^6 in frictional engagement with the collar n^7 .
- 5 10 When the engaging face n^{10} is brought into engagement with the collar n^7 the arm n will be moved so that its extension n' will engage the cam lever b^8 and move it into the second dotted line position shown in Fig. 3, in which position the tension of the needle thread is wholly relieved, and when the engaging face n^9 is brought into engagement with the collar n^7 the arm n will be moved in the opposite way and the cam lever b^8 thereby permitted to return to the full line position shown in Fig. 3 and a hard tension applied. Thus whenever it is desired to wholly relieve the tension the drive-wheel or shaft will be turned backward by hand, and whenever it is desired to restore the tension the drive-wheel or shaft will be turned in the opposite way, either by hand or by starting the machine in the regular manner. The means for wholly relieving the tension is thus operated by hand, but under ordinary conditions will be automatically restored.
- 15 20 25 30 It will be observed that the means for operating the tension device is positively actuated in opposite ways upon the initial movement of the rotating member in both directions, or upon reversing the rotation of the rotating member in both directions.
- Claims:
1. In a sewing machine, a thread-wheel, 40 a friction-disk bearing upon it, two concentrically disposed springs acting in the same direction to exert their combined pressures upon said disk and means for operating one or both of said springs to respectively partially or wholly relieve the tension, substantially as described.
2. In a sewing machine, a thread-wheel, a friction-disk bearing upon it, two concentrically disposed springs acting in the same direction to exert their combined pressures upon said disk, a cam-lever and means operated by it for operating one or both of said springs to respectively partially or wholly relieve the tension, and means for operating said cam-lever, substantially as described.
3. In a sewing machine, a thread-wheel, a friction-disk adapted to bear upon it, a spring which exerts its pressure upon said friction-disk, a ring adapted to engage said friction-disk, a spring which exerts its pressure upon said ring, a pin passing through a slot in the hub of the friction-disk which is connected with said ring and means for moving said pin, substantially as described.
4. In a sewing machine, a thread-wheel, a friction-disk adapted to bear upon it, a spring which exerts its pressure upon said friction-disk, a ring adapted to engage said friction-disk, a spring which exerts its pressure upon said ring, a pin passing through a slot in the hub of the friction-disk which is connected with said ring, a rod contained in the shaft bearing the thread-wheel to which said pin is rigidly connected and means for moving said rod longitudinally, substantially as described.
5. In a sewing-machine, a thread-wheel, a friction disk bearing upon it, two concentrically disposed springs acting in the same direction to exert their combined pressures upon said disk, an axially movable hand-wheel and a ring axially movable on said hand-wheel against which said springs bear respectively, and means movable in the same direction to operate one or both of said springs according to the distance moved to partially or wholly relieve the friction, substantially as described.
6. In a sewing-machine, a tension-device, means for operating it, and an operating-device for said means, comprising an arm having a two-faced collar-engaging end portion provided with an intermediate projection, and a rotatable collar having a recess adapted to receive said projection and thereby move said arm to bring either one of its engaging-faces into concentric relation to the collar, substantially as described.
7. In a sewing-machine, a tension-device, means for operating it, and an operating-device for said means comprising an arm having a two-faced collar-engaging end portion provided with an intermediate projection, and a rotatable collar secured to the main shaft of the machine, having a recess adapted to receive said projection and thereby move said arm to bring either one of its engaging-faces into concentric relation to the collar, substantially as described.
8. In a sewing machine, a tension-device, means for operating it to relieve the tension on the thread comprising a cam-lever, a pivoted spring controlled arm, an arm loosely connected to said pivoted arm having a two-faced collar-engaging end-portion provided with an intermediate projection, and a rotatable collar having a recess adapted to receive said projection and thereby move said arm to bring either one of its engaging faces into concentric relation to the collar, substantially as described.
9. In a sewing machine, a tension-device, means for operating it comprising a cam-lever and an operating-device therefor comprising an arm having a two-faced collar-engaging end-portion provided with an intermediate projection, and a rotatable collar having a recess adapted to receive said projection and thereby move said arm to bring either one of its engaging faces into concentric relation to the collar, substantially as described.

concentric relation to the collar, substantially as described.

10. In a sewing machine, a tension device, means for operating it, an operating device 5 for said means, comprising an arm having two collar-engaging faces with an intermediate projection, and a rotatable collar having a recess adapted to receive said projection and thereby move said arm to bring 10 either one of its engaging faces into engagement with the collar, substantially as described.

11. In a sewing machine, a tension device, means for operating it, actuating-mechanism 15 for said means comprising a pivoted member and an arm loosely connected to said member having two collar-engaging faces and an intermediate projection, and a rotatable collar having a recess adapted to 20 receive said projection and thereby move said arm to bring either one of its engaging faces into engagement with the collar, substantially as described.

12. In a sewing machine, a tension device, means for operating it, actuating-mechanism 25 for said means comprising a pivoted member and an arm loosely connected to said member having two collar-engaging faces and an intermediate projection, and a 30 rotatable collar having a recess adapted to receive said projection and thereby move said arm to bring either one of its engaging faces into engagement with the collar, and a spring for continuously holding said 35 actuating-mechanism in engagement with said collar, substantially as described.

13. In a sewing machine, a tension device, means for operating it comprising a cam lever, a pivoted arm adapted to engage 40 said cam lever, an arm loosely connected to said pivoted arm having two collar-engaging faces and an intermediate projection, a rotatable collar having a recess adapted to receive said projection and thereby move 45 said arm to bring either one of its engaging faces into engagement with the collar, substantially as described.

14. In a sewing machine, a tension-device, means for operating it, including a lever 50 having a toothed member connected with it and a rotating member having provision for engagement with and for positively operating the toothed member upon reversing

the rotation of said rotating member in either direction to release the tension upon 55 backward rotation of said rotating member and to apply the tension upon the forward rotation thereof.

15. A tension releasing-device, having, in combination, a rotating member, a tension-wheel, and connections between the rotating member and tension wheel consisting of a positively operating device for releasing the tension upon reverse rotation of the rotating member and frictional means for 65 throwing the positively operating device into operation.

16. A tension releasing-device, having, in combination, a rotating member, a tension-wheel, connections between the rotating 70 member and the tension wheel for releasing the tension upon a reverse movement of the rotating member, comprising a positively acting device for releasing the tension, frictional means for throwing the positively 75 acting device into operation and frictional means for throwing said positively acting device out of operation.

17. A tension releasing-device, having, in combination, a tension wheel, a rotating 80 member, connections between the tension wheel and the rotating member including an oscillatory member provided with two friction surfaces adapted to engage said rotating member and located at different distances from the pivot of said oscillating member so that each of said surfaces will 85 hold the releasing connections inoperative.

18. A tension releasing device, having, in combination, a tension wheel, means for 90 applying pressure thereto, a rotating member, connections between the rotating member and the pressure applying means including an oscillatory member provided with a tooth and two frictional surfaces located upon opposite sides of said tooth at 95 different distances from the center of motion of the oscillating member.

In testimony whereof, I have signed my name to this specification, in the presence of 100 two subscribing witnesses.

WILLIAM C. MEYER.
